UNITED STATES PATENT OFFICE.

Specification of a New and Useful Improvement in
Remote-Control Switches, of which the following is a
description and drawing of the invention, for the
obtaining a patent for the same, it being understood
that no claim is made to any new combination of
elements, or to any element in a new combination
with other elements, except as so specifically set
forth in the claims.

1,146,340. Remote-Control Switch. Specified of Letters Patent. Patented July 13, 1915.

By WALTER S. MAYER, of Taunton, Massachusetts, filed December 19, 1914. Serial No. 878,106.

To all whom it may concern:—Be it known that I, WALTER S. MAYER,

a citizen of the United States, residing at
Taunton, Massachusetts, have invented cer-
tain new and useful Improvements in Re-
mote-Control Switches, of which the follow-
ing is a specification.

Among the objects of the invention are
to simplify the construction of switches of
this class. This simplification is largely
effected by placing one of the switch coils
inside of the other and by using a common
internal magnetic circuit. The bridging
member or electrical connector of the switch
proper is one continuous piece and at the
same time this bridge, or portions of it, act
as a spring for breaking the circuit.

The characteristics and advantages of the
invention will be further pointed out, so far
as is necessary, in connection with a detailed
description of the accompanying drawing,
which illustrates one exemplifying embodiment
of the invention. It is to be under-
stood that the invention is capable of em-
bodiment in other forms, and I do not limit
myself to the details except as claimed here-
inafter.

In the drawings: Figure 1 is a side view
partly in elevation and partly in section of
switch mechanism embodying the invention.
Fig. 2 is a top plan of the same. Fig. 3 is
a left hand elevation. Fig. 4 is a side eleva-
tion of the central part of the device
partly in section to show more particularly
the latch mechanism. Fig. 5 is a diagram of
circuits.

Reference character 1 designates a base to
which is secured a metallic core piece 2 having
magnet core 3 and uprights 4, 5. About
40 the core 3 is placed a closing magnet coil 6
and within the hollow core is an opening
magnet coil 7. Within the spool-shaped
magnet coil 7 is a movable armature or
plunger 8 having a non-magnetic stem 9 pro-
jecting through an aperture in the top piece
of core 3. Plunger 8 has a head 10 engaged
by a spring 11 abutting against the bottom
of the magnet spool to yieldingly hold plun-
ger 8 down for reasons which will appear.
Pivoted to upright 4 is main armature or
magnetic bridge piece 12, which carries the
main conductor or bridge 13, preferably of
laminated construction, the laminations be-
ing composed of strips of copper. One end
55 of the conductor bridge 13 is connected to

the end of the bridge 13 being connected to the main
conductor or bridge 13, the other end of the bridge 13 being connected to the main conductor or bridge 13.

At 14 the bridge is bent into part-circular
form, and this part of it constitutes a spring
to open the circuit. At the movable end of
the bridge one of the laminæ is provided

with an arcing tip 15 which may be renewed,
and this lamina is so arranged that it will
maintain contact of the arcing tip with ter-
minal C on the base and the other or move-
able end of the bridge is to make a breaking
contact with terminal B on the base.

At 14 the bridge is bent into part-circular
form, and this part of it constitutes a spring
to open the circuit. At the movable end of
the bridge one of the laminæ is provided
with an arcing tip 15 which may be renewed,
and this lamina is so arranged that it will
maintain contact of the arcing tip with ter-
minal B after the other laminae have broken
contact, and thus the arcing tip will take the
arc and protect the remainder of the bridge.

Frame member 5 carries side plates 5¹ of
insulating material and these support a de-
tent roller 16 rotatably mounted upon a pin
17. To coöperate with this the main arma-
ture 12 carries a latch or hook 18 pivoted
at 19 and urged by a spring 20 so that the
hook will engage the roller when the arma-
ture is depressed. The hook carries an ex-
tension or trigger 21, the end of which en-
gages with the end of plunger pin 9, the
armature 12 and circuit bridge 13 being
apertured at 22 to permit pin 9 to engage the
trigger.

Base 1 carries terminals D and E for the
controlling circuit. Frame member 5 car-
ries binding posts F and G suitably insu-
lated. One conductor from the controlling
station is connected to the remote control
base 1 at D and the other similar conductor
at E. One control circuit passes from E to
the closing coil and from the coil to binding
post G. The other control circuit passes
from D to the opening coil and from the coil
to binding post F. From these points the cir-
cuit is controlled by an automatic auxiliary
switch, shown in Fig. 3. This comprises a
spring-arm 23 connected to a bell-crank mem-
ber 24, which is in turn pivoted at 25
to a conducting strip 26, and this strip is in
turn connected to a binding post H, the strip
and binding post being supported upon
frame member 5, but suitably insulated.
From binding post H, a conductor common
to both the opening and closing magnet coils,
goes to the control station. Bell-crank mem-
ber 24 is urged to the position shown in Fig.
3 by a spring 27, and arm 28 of the bell-
crank is actuated upon by an insulated stud
29 carried by the main armature 12.

When the circuit controlled by the main
switch is open, with the parts being in the
position shown in Figs. 1 and 3, to close the
110

main circuit the closing coil 6 is energized, thus causing armature 12 to be attracted to core 3. This swings the free ends of the conductor bridge into engagement with the terminal B, closing the circuit. At the same time, latch 18 strikes roller 16, is retracted, passes and engages with the roller and holds the armature down against the effort of spring member 14. In closing, armature 10 stud 29 (Fig. 3) strikes bell-crank arm 28 and moves the end of spring-contact-member 23 from engagement with binding post G, thus breaking the circuit through the closing coil and engages the spring member 15 23 with binding post F, thus closing the circuit through the opening coil so far as this part of the mechanism is concerned. When the controlling switch is properly actuated 20 at the controlling station to complete the opening circuit, the opening coil 17 is energized, plunger 8 is thus raised against its spring 11 and stem 9 acts upon trigger 21 to release hook 18 from detent roller 16. The spring member thereupon raises the 25 armature and breaks the main circuit. Stud 29 at the same time releases bell-crank 24 and the movable contact 23 leaves binding post F and engages with G, thus breaking the opening circuit and reestablishing the 30 closing circuit so far as the remote control switch is concerned ready for the next closing action.

When the closing coil is energized, it exerts some pull upon the plunger 8 and to 35 counteract this the spring 11 is provided. When the opening coil 7 is energized its pull is sufficient to overcome the spring and raise the plunger as above described.

At the pivoted connection 12^a of the main 40 armature 12, a finger 12^b is provided to engage frame member 4 and limit the opening movement.

The provision of a roller 16 as a detent member for the latch may not in all cases be 45 essential, but it provides an easy and improved latch action, and will, therefore, usually be preferable.

Fig. 5 shows a suitable controlling circuit. S designates a generator or other source of 50 current. Positive and negative lines are designated by conventional characters and the bridge or movable conductor 13 of the armature of the remote control switch is shown inserted in the positive line. The main circuit is open and the control switch K at the station is shown in open position. The auxiliary switch 23 at the remote control point is shown in circuit with the closing coil 6. When it is desired to close the main circuit, 55 switch K is thrown over. A circuit is thus established from the current source through the negative line, to and through the closing coil 6, and back through switch 23 to the positive side of the generator. The closing 60 movement of the main armature throws aux-

iliary switch 23 into engagement with contact F and the circuits are then ready for an opening action in an obvious manner.

An important feature of the invention is that the switch unit shown, which corresponds to a single pole device, may be duplicated for a double pole switch, and so on, without any modification or difficulty other than connecting the additional switches in a suitable way. Another important feature, 70 as above explained, is the utilization of the laminated conductor 13 as a spring member to effect opening of the switch. Another important feature is the simplicity resulting from the arrangement of the switch coils one 75 within the other and their combination with a hollow core piece, as shown, and the utilization of a common internal magnetic circuit. Another important feature is the direct action provided. The pull of the closing coil is exerted directly on the main armature to which the bridge is firmly and directly attached. The latch and trigger being directly mounted on the armature also provides great simplicity and positiveness 80 of action. Another important feature is the location of the magnets directly beneath the main armature.

I claim:—

1. In a switch of the class described, the 95 combination of a base, a magnet frame comprising uprights and a hollow core piece, a magnet surrounding the core, a magnet within the core, a main armature pivoted to one of the uprights, a movable main contact carried thereby, latch mechanism intermediate the main armature and one of the uprights, and an auxiliary switch actuated directly by the main armature for controlling the circuit through said magnet. 100

2. In a switch of the class described, the combination of a base, a magnet frame comprising uprights and a hollow core piece, a magnet coil surrounding the core, a magnet within the core, a main armature pivoted to 110 one of the uprights, a movable main contact carried thereby, latch mechanism intermediate the main armature and one of the uprights, a releasing armature co-operating with said inner coil and said latch mechanism, and an auxiliary switch carried by one 115 of the uprights and actuated directly by the main armature for controlling the circuit through said coils.

3. In a switch of the class described, the 120 combination of main terminals, a main armature, a contact carried thereby for connecting the terminals, a tubular core adjacent to the armature, a magnet coil placed about the core, a magnet coil located within 125 the core, latch mechanism for the main armature and a releasing armature within the inner coil for actuating the latch mechanism.

4. In a switch of the class described, the 130

- combination of main terminals, a frame-piece comprising a tubular core, a main armature pivoted to the frame-piece, a contact carried by said armature for connecting the terminals, a magnet coil placed about the core, a magnet coil located within the core, latch mechanism for the main armature and means acted upon by the magnetic circuit of one of said coils for operating said latch mechanism, the magnetic circuit of the other of said coils serving to move the main armature to closed position.
5. In a switch of the class described, the combination of main terminals, a frame-piece comprising a tubular core, a main armature pivoted to the frame-piece, a contact carried by said armature for connecting the terminals, a magnet coil placed about the core, a magnet coil located within the core, latch mechanism for the main armature and means acted upon by the magnetic circuit of one of said coils for operating said
- 10
- 15
- 20

latch mechanism, the magnetic circuit of the other of said coils serving to move the main armature to closed position, and an auxiliary switch actuated by the main armature to control operating circuits through said coils.

6. In a switch of the class described, the combination of main terminals, a main armature, a contact carried thereby for connecting the terminals, a tubular core adjacent to the armature, a magnet coil placed about the core, a magnet coil located within the core, latch mechanism for the main armature, a releasing armature within the inner coil for actuating the latch mechanism, and an auxiliary switch actuated by the main armature and serving to control circuits through said coils.
